(57) **CLAIM**

The ornamental design for a Pitching Device as shown and described.

DESCRIPTION

FIG. 1 is a perspective view of a Pitching Device showing my new design;

FIG. 2 is a front view thereof;

FIG. 3 is a left side view thereof;

FIG. 4 is a perspective view showing the design in an alternate position and in association with broken lines illustrative of its intended use; and

FIG. 5 is a perspective view showing the design in another alternate position and in association with broken lines illustrative of its intended use.

The drawings contain a symbolic break in FIGS. 1 & 2 in order to fit the article on the page. The break lines form no part of the claimed design. The broken lines depicting the diagonal on the cord in FIG. 1 are for illustrative purposes only and form no part of the claimed design.

The evenly spaced dashed lines on the pitching device depict portions of the article that form no part of the claimed design. The evenly spaced dashed lines in FIGS. 4 & 5 showing a coach, player, and base depict environment and form no part of the claimed design.
